**COMBINED STEERING WHEEL AND CONTROL
MEANS FOR OUTBOARD MOTORS**

Harvard J. Gerstner, Minneapolis, Minn.

Application May 17, 1957, Serial No. 46,215

Term of patent 14 years

(Cl. D71—1)

FIG. 1

FIG. 2

Figure 1 is a side view of the combined steering wheel and control means for outboard motors.

Figure 2 is a top plan view of the combined steering wheel and control means for outboard motors.

The sides of the housing element not shown are substantially plain, and the side of the article opposite that shown in Fig. 1 is substantially the same in appearance as the side shown.

I claim:

The ornamental design for a combined steering wheel and control means for outboard motors, as shown and described.
